[57] CLAIM

The ornamental design for a combined brush and ice scraper, or the like, substantially as shown and described.

DESCRIPTION

FIG. 1 is a plan view of a combined brush and ice scraper or the like showing my new design;

FIG. 2 is a side elevational view thereof;

FIG. 3 is an end elevational view taken along line 3—3 of FIG. 2;

FIG. 4 is an end elevational view taken along line 4—4 of FIG. 2;

FIG. 5 is a side elevational view of the side opposite that shown in FIG. 2; and

FIG. 6 is a bottom view thereof.

Fig. 4
